Samuel M. Gibbs

Samuel H. Gibbs of Albany, N. Y. Ass on to
Jagger, Treadwell & Perry.
Letters Patent No. 359 Dated Mar. 4, 1851.

The Schedule referred to in these Letters Patent and making part of the same.

To all whom it may concern:

Be it Known

that I, Samuel H. Gibbs, of Albany, in the County of Albany and State of New York, have invented, or produced, a new ornamental design for an air-tight Box Stove - And I do hereby declare that the accompanying drawings, making part of this specification, are full and accurate representations of a stove, after my said design. - Fig. 1 being a perspective view, showing the general form of the stove. - Fig. 2 is a front view - Fig. 3 the hearth plate, and Fig. 4. a portion of the top plate - upon a larger scale, in order to show the detail of ornaments. The back of my stove is precisely similar to the front, and the sides are also formed by a succession of similar ornamental arches.

What I claim as my invention, and desire to secure by Letters Patent, is the combination and arrangement of ornamental figures, shown in the accompanying drawings, forming a new ornamental design for an air-tight Box-Stove.
